(57) **CLAIM**

(21) Appl. No.: **29/326,561**

The ornamental design for a strategic pattern building board game, as shown and described.

(22) Filed: **Oct. 20, 2008**

DESCRIPTION

(51) **LOC (9) Cl.** 21-01

FIG. 1 is a perspective view of the strategic pattern building board game of the instant invention;

(52) **U.S. Cl.** **D21/337**

FIG. 2 is a front elevational view thereof;

(58) **Field of Classification Search** D21/334-368;
273/236-288

FIG. 3 is a rear elevational view thereof;

See application file for complete search history.

FIG. 4 is a right side elevational view thereof; and,

(56) **References Cited**

FIG. 5 is a left side elevational view thereof.
